COMBINED WALLET AND CARD CASE

Jerome F. Coniker, Highland Park, Ill., assignor to
Coniker Enterprises, Inc., Chicago, Ill., a corpora-
tion of Delaware

Filed July 28, 1965, Ser. No. 86,862

Term of patent 14 years

(Cl. D87—3)

FIGURE 1 is a front perspective view of a combined wallet and card case, showing my new design, in folded or closed condition;

FIGURE 2 is a right side elevational view thereof;

FIGURE 3 is a front elevational view thereof in unfolded or open condition.

The characteristic feature of my design resides in the combination, on the wallet/case disclosed, of a plurality of overlapping pass leaves on one inner side opposite a dependent flap and a pocket on the other inner side, in conjunction with embossed, centrally-disposed vertical fold lines, all as shown.

This application is a continuation-in-part of my co-pending application Ser. No. D. 86,066, filed July 8, 1965, and now abandoned.

I claim:

The ornamental design for a combined wallet and card case, as shown and described.
